UNITED STATES PATENT OFFICE.

FRANK GILBERT HINSDALE, OF NEW YORK, N. Y.

METHOD OF AND APPARATUS FOR INSPECTING AND SEARCHING LACE FABRICS.

Original application filed January 12, 1923, Serial No. 612,176. Divided and this application filed October 29, 1925. Serial No. 65,541.

My invention relates to the manufacture of lace fabrics such as lace curtains, and has for its object to provide a novel and simple apparatus for inspecting and searching the curtains or other lace fabric for defects and imperfections and to detect deficiencies in the weaving thereof. Other objects of the invention will appear from the description hereinafter and the features of novelty will 5 be pointed out in the claims. The present application is a division of another application filed by me on January 12, 1923, Serial No. 612,176.

Reference is to be had to the accompanying drawings, which illustrate examples of the invention without defining its limits, and in which Fig. 1 is a diagrammatic view illustrating the novel method; Figs. 2 and 3 are front and end views respectively illustrating 10 examples of the improved apparatus which may be used for carrying out the method; Fig. 4 is a horizontal section on the line 4—4 of Fig. 5; Fig. 5 is a fragmentary vertical section on the line 5—5 of Fig. 4; Fig. 6 is a fragmentary detail view illustrating latch members forming part of the apparatus and Fig. 7 is a fragmentary section on the line 15 7—7 of Fig. 6.

In describing the method, reference will 20 be had to the diagrammatic illustration of Fig. 1. The lace fabric in the form of curtains or otherwise, after having been woven in any usual manner may be doffed from the loom in any convenient way, and then is inspected and searched in the following novel manner, this being done to check up the work of the weaver and to detect poor weaving and other defects and imperfections in the curtains.

The lace curtains or other lace fabrics of a given weaving operation are first preferably all sewed together in a continuous length or web and wound up on a spit-bar in a roll *a* from which the lace fabric is withdrawn over a canvas screen *b* and rolled up on a roll *c*. While the lace fabric passes over the screen *b*, a careful search is conducted for such imperfections as may exist therein; as each imperfection is found, the travel of the lace fabric from the roll *a* to the roll *c* is temporarily suspended and said lace fabric is amended to cure said imperfection, for instance by being drawn around a mending machine *d*, whereby the mending is performed, the machine *d* being located in close

proximity to the screen *b*. After this has been done, winding of the lace fabric from the roll *a* to the roll *c* is resumed until the next imperfection is reached, whereupon the same is mended, this operation being repeated as often as required until the lace fabric has been completely transferred from the roll *a* to the roll *c*. 60

Subsequently the lace fabric may be made up into kier lots, or said fabric may be 65 otherwise disposed of.

While the improved method may be carried out in any convenient manner, the machine shown by way of example in Figs. 2—7 of the drawings is preferred for this purpose. 70

This machine comprises a base 10 and oppositely located uprights 11 provided at their upper ends with recesses 12 and with longitudinally extending slots 13; a tie-rod 14 connects the uprights 11 to stabilize the machine. At their upper ends said uprights carry outwardly projecting arms 15 secured in place in any convenient manner and connected by means of a guide rod 16; a similar 75 guide rod 17 is fixed in brackets 18 secured to said uprights near the base 10.

A drum 19 is journaled in suitable bearings on the uprights 11 and at its one end is provided for instance, with a bevel gear 20. 80 The latter is arranged in mesh with a bevel pinion 21 mounted upon a countershaft 22 rotatably mounted in bearings 23 and carrying loosely a pulley 24 arranged for connection with a motor or other source of power; a suitable clutch 25 is provided for operatively connecting the pulley 24 with the shaft 22 when it is desired to operate the machine. The latter further includes slides 26 movable lengthwise of the slots 13 and each provided with pivoted latch members 27 for the reception of a spit-bar 28. In the illustrated example, the arrangement 85 comprises duplicate latch members 27 provided with recesses 29 for the reception of the ends of said spit-bar 28 and having lugs 30 projecting from said recesses for the purpose to be more fully set forth hereinafter. The latch members 27 includes suitable manipulating handles 31 and are pivoted at 32 upon the slides 26 which as previously set forth are fitted to slide vertically in the slots 13 of the uprights 11, suitable stops 33 being provided on said slides for arresting the pivotal movements of said latch members in 100 105 110 115 120 125 130 135 140 145 150 155 160 165 170 175 180 185 190 195 198 200 205 one direction. The slides themselves may be slidably fixed in said slots by means of plates 34 clamped in place by means of clamp screws 35 and clamp nuts 36, springs 37 being provided for maintaining said clamp nuts 36 against unintentional loosening; as shown in the drawings, the clamp screws 35 may comprise integral parts of the stops 33, it being understood that, normally, the clamp screws 35 serve to maintain the parts of the slides in operative connection without interfering with the sliding movements thereof in the slots 13. If desired, liners 38 of fibre or other suitable material may be located between the slides 26 and the uprights 11 and between said slides and the plates 34, as illustrated in Fig. 7.

In utilizing the searching machine shown in the drawings, the spit-bar on which the roll of lace *a* is supported is placed in the recesses 12 to rotatably support said roll of lace *a* upon the uprights 11 and the lace is drawn over the guide-rods 16 and 17 and inwardly from the latter to the spit-bar 28. As the drum 19 is rotatably actuated through the medium of the gearing 20, 21 and countershaft 22, said spit-bar 28 will be rotated in a direction to wind the lace thereon in the form of the roll *c*. During the transfer of the lace from the roll *a* to the roll *c*, it passes over the guide-rods 16 and 17 and, between the latter, presents the form of a vertical panel capable of being quickly and thoroughly searched for defects; in the preferred construction the screen *b* of canvas, previously referred to, is located behind the lace in registry with said vertical panel and is supported in any convenient manner as by being suitably attached to the arms 15 and brackets 18 for instance by means of clips *b'*. A work board 39 may be included in the searching machine to facilitate this searching of said lace. As the winding up of the lace upon the spit-bar 28 proceeds and the diameter of the roll of lace *c* progressively increases, the spit-bar 28 will gradually move away from the drum 19 and raise the slides 26 in the slots 13; during this operation clamp nuts 36 are loosened and the ends of the spit-bar 28 are journalled in the recesses 29 of the latch members 27 and are held thereby against displacement whereby the roll of lace *c* is maintained in proper operative relation to said drum 19. When the aforesaid operation has been completed, the clamp nuts 36 are tightened to fix the slides 26 in place and the latch members 27 are thrown up on the pivots 32 by means of the handles 31, which causes the lugs 30 to raise the spit-bar 28 and its roll of lace *c*, whereby the latter is lifted away from the drum 19 a

sufficient distance to clear the same; in this position of the latch members 27, the recesses 29 are outwardly open, so that the spit-bar 28 may be rolled forwardly on said lugs 30 and easily removed from the machine with the roll of lace *c*. It will be understood that, in practice, the searching machine just described is preferably located in operative proximity to the mending machine *d* so that as defects in the lace are discovered, the mending thereof may be immediately accomplished as previously set forth.

Various changes in the specific form shown and described may be made within the scope of the claims without departing from the spirit of my invention.

I claim:

1. A searching machine for lace fabrics in the form of continuous webs, comprising a base, brackets projecting outwardly from said base in spaced relation to each other, a lower guide rod extending between and carried by said brackets, oppositely located uprights projecting upwardly from said base and provided at their upper ends with open recesses for rotatably supporting a roll of fabric, arms projecting outwardly from said uprights, an upper guide rod extending between and carried by said arms, said web of fabric passing from said roll over said guide rods and being positioned thereby in the form of a vertical panel, and mechanism on said base whereby said web of fabric is rewound in the form of a roll after it passes over said lower guide rod.

2. A searching machine for lace fabrics in the form of continuous webs, comprising a base, brackets projecting outwardly from said base in spaced relation to each other, a lower guide rod extending between and carried by said brackets, oppositely located uprights projecting upwardly from said base and provided at their upper ends with open recesses for rotatably supporting a roll of fabric, arms projecting outwardly from said uprights, an upper guide rod extending between and carried by said arms in vertical registry with said lower guide rod, a screen located in vertical position between said guide rods, clips on said screen for connecting it with said guide rods, said web of fabric passing from said roll of fabric over said guide rods and screen in the form of a vertical panel, and mechanism on said base whereby said web of fabric is rewound in the form of a roll after it passes over said lower guide rod.

In testimony whereof I have hereunto set my hand.

FRANK GILBERT HINSDALE.
